PHILO E. TINGLEY, OF NEW YORK, N. Y.

LINE-SPACING ATTACHMENT FOR WRITING-MACHINES.

1,103,103.

Specification of Letters Patent. Patented July 14, 1914.

Application filed July 9, 1913. Serial No. 773,160.

To all whom it may concern:

Be it known that I, PHILO B. TINGLEY, a citizen of the United States, residing at New York city, county of New York, State of New York, have invented an Improvement in Line-Spacing Attachments for Writing Machines, of which the following is a specification.

This invention has for its object to produce a line spacing attachment which shall be supplemental to the regular line spacing device of a writing machine and may be applied to new or old machines and which will enable the operator to give to the lines any required uniform spacing, to space irregularly or to re-align with perfect accuracy a sheet that has been removed.

It is of course well understood that in writing machines as ordinarily constructed the spacing of the lines is effected by the engagement of a pawl with the teeth of a ratchet wheel, three spacings being ordinarily provided which are known as single, double and triple spaces. My novel attachment is supplemental to this ordinary spacing device which may be used in lieu of the attachment if preferred. Should it be required to space irregularly, however, as in filling in blanks, or should a spacing be required other than the three arbitrary spacings provided by the spacing device of the machine, or should it be desired to approximately fill a sheet of limited size with a certain number of lines which would not correspond with either of the three arbitrary spacings provided by the machine, it would be necessary to throw off the spacing attachment and space each line by guesswork by rotation of the platen, and frequently to shift the paper relatively to the platen; that is, to draw the paper while holding the platen stationary. These difficulties are wholly overcome by the use of my novel spacing attachment in which the forward movement of the platen is effected by the action of an oscillatory collar and a gripping roller, the action of the collar being adjustable so as to cause the roller to grip the platen at the required instant to produce the required line space by actuation of the usual spacing device of the machine.

With the above stated and other objects in view I have devised the novel attachment which I will now describe referring to the accompanying drawing forming a part of

this specification and using reference characters to indicate the several parts.

Figure 1 is a detail elevation of so much of an L. C. Smith & Bros. writing machine as is necessary to illustrate the spacing mechanism thereof and to show how my novel attachment is applied to the machine; Fig. 2 an elevation of the right end of the platen detached, showing the spacing ratchet wheel and the handle for rotating the platen; Fig. 3 an elevation of the attachment with the collar in its normal or retracted position, the platen being in section on a line indicated by 3-3 in Fig. 2, looking in the direction of the arrows, it being noted, however, that in Fig. 2 the attachment is omitted; Fig. 4 an edge view of the attachment as seen from the right in Fig. 3, the adjustable link being removed; Fig. 5 a view corresponding with Fig. 3 but showing the collar in its forward or operated position, that is at the end of a spacing operation; Fig. 6 a view corresponding with Fig. 3 but showing the invention as applied to a Remington machine and also showing a modified form of adjustable link; Fig. 7 a detail sectional view of the tubular member of the adjustable link, detached, corresponding with Figs. 3 and 5; Fig. 8 an inverted plan view of the scroll wheel detached, corresponding with Figs. 3 and 5; Fig. 9 a plan view corresponding with Fig. 7, the scroll wheel being removed; Fig. 10 an elevation corresponding with Fig. 7, and Fig. 11 is a plan view and Fig. 12 an elevation of the toothed slide detached.

It should be understood that the invention is equally applicable to any of the various types and makes of writing machines in general use, certain parts only requiring to be changed and the principle being the same in all cases.

20 denotes the platen and 21 the spacing ratchet wheel which is detachably secured to the right end thereof. The platen is ordinarily shouldered, and the spacing ratchet wheel forms with the shoulder a groove 22 which receives the oscillatory collar of my novel attachment, as will be more fully explained.

The ordinary spacing mechanism comprises essentially a line space lever 23, a bell crank lever 24 and a spacing pawl 25 pivoted to the bell crank lever and engaging the spacing ratchet wheel. The spacing

105

110

ratchet wheel is normally engaged also by a roller 26 carried by a spring arm 27 which is rigidly secured to a fixed portion of the machine. This roller by engagement with the teeth of the ratchet wheel retains the platen in any position in which it may be placed. The roller is thrown out of engagement with the ratchet wheel by means of a lever 28. The various intermediate parts are not shown, and this mechanism is not illustrated or described in detail, as it forms no portion of the present invention and moreover differs in the various machines in general use.

My novel attachment comprises an oscillatory collar 29 mounted on the end of the platen, in the present instance in groove 22, and having an enlargement provided with an elongated socket 30 to receive a gripping roller 31. It will be noted that the lower portion of the socket is of less width than the diameter of the roller while the upper end of the socket is of greater width than the diameter of the roller. A lever 32 pivoted in the enlargement is provided in order to lift the roller out of engagement with the platen when it is desired to move the platen backward, or to entirely release it, as indicated by the full line position of the roller in Fig. 3, or to use the ordinary spacing mechanism. The dotted position of the roller in Fig. 3 is its normal position. When the collar is in the position shown in Fig. 3 with the roller in the dotted position, forward movement of the collar (i. e. upward movement from right toward left) will cause the roller to wedge between the wall of the recess and the platen and will carry the platen forward. The instant backward movement of the collar begins the collar will move downward away from the roller leaving the roller in the wider upper portion of the recess so that this backward or downward movement of the collar will be free, leaving the platen in the position to which it has been carried by the forward movement. The oscillations of the collar are effected by means of an adjustable reciprocating link 33 which is pivoted to bell crank lever 24 and to an arm 34 extending from the oscillatory collar. In the form illustrated in Figs. 3, 5 and 7 to 11, inclusive, the link comprises a tubular member 35, a toothed slide 36 and a scroll wheel 37 provided with a finger piece 38. The scroll wheel is mounted to oscillate on a stud 39 and is retained in place by a nut 40. The scroll 41 on the scroll wheel engages the teeth 42 on the slide and causes the slide to reciprocate within the tubular member to lengthen or shorten the link and cause more or less forward movement of the collar, and consequently a greater or less space between the lines printed by the machine. I have shown the tubular member as provided with a slot 43 at one end of which is a projection 44. The

toothed slide is provided with a projection 45 which extends through the slot as clearly shown in Figs. 3 and 5. A scale 46 may be provided on opposite sides of the slot so graduated that the space between projections 44 and 45 will correctly indicate the space between lines printed by the machine. In Figs. 3 and 5, the link is shown as shortened to the extreme of its movement, which would produce the longest space within the capacity of the attachment. The space is shortened by lengthening the link, which is effected by rotation of the scroll wheel to move the toothed slide outward. As a means for limiting the forward movement of the collar, I provide a lug 47 thereon which at the extreme of the forward movement of the collar will engage a suitable stop, as the hub 48 carried by spring arm 27 on which roller 26 rotates.

In Fig. 6, I have illustrated the application of the invention to a Remington writing machine. The oscillatory collar is provided with an arm 49, the spacing pawl 50 is pivoted to a reciprocating bar 51 and the adjustable link 52 is pivoted to the upper end of the spacing pawl and to arm 49. The space between lines printed by the machine is shortened by shortening the link and is lengthened by lengthening the link. The link in this form comprises a screw 53 pivoted to arm 49, a screw 54 pivoted to spacing pawl 50, a nut 55 engaging both screws and a lock nut 56 to retain the nut in position after adjustment. A pin 59, projecting from a fixed portion of the machine, is provided for engagement by lug 47 on the collar to limit the forward movement of the collar. The socket in the enlargement of the collar is closed on opposite sides by cover plates 57. In order to lock gripping roller 31 out of operative position, as in full lines in Fig. 3, when it is not desired to use the attachment, I provide one of the cover plates with a projection 58 which may be made by indenting the metal of the cover plate, see Fig. 6, which shows the indentation on the outer side of the cover plate which forms the projection on the inner side. In throwing the roller to the inoperative position, lever 32 is swung past the projection which acts to retain it in that position and to retain the roller out of engagement with the platen.

The operation is as follows: If the attachment has been in use and it is desired to use the ordinary spacing device of the machine, the gripping roller is thrown out of engagement with the platen, as in Fig. 3, and the link is adjusted to its longest length and spacing pawl 25 is turned into operative position as in dotted lines in Fig. 1. The condition of the machine is then precisely the same as if the attachment had not been applied. Suppose now that it is desired to use the attachment. Spacing pawl 25 is

thrown out of operative position as in full lines in Fig. 5 and lever 32 is moved to the dotted position in Fig. 3 which permits the gripping roller to drop down into operative position. The space between the lines printed by the machine is determined by the length of the link which is adjusted to the requirements of use and will produce any required spacing within the capacity of the machine. If it is required to print a line and then to space regularly from that line, the paper is placed in position to print that line and then spacing by the attachment will proceed from that line as already described.

Having thus described my invention I claim:

1. A line spacing attachment for a writing machine platen comprising an oscillatory collar having a projecting arm and an enlargement with a socket widest at its upper end, a roller adapted to wedge between the wall of the socket and the platen, for the purpose set forth, and a reciprocating link pivoted to the arm for oscillating said collar.

2. A line spacing attachment for a writing machine platen comprising an oscillatory collar having an enlargement with a socket widest at its upper end, a roller adapted to wedge between the wall of the socket and the platen and a link for oscillating the collar comprising a tubular member, a toothed slide therein and a scroll wheel on the tubular member which engages the slide.

3. A line spacing attachment for a writing machine platen, comprising an oscillatory collar having an enlargement with a socket widest at its upper end, a roller adapted to wedge between the wall of the socket and the platen and a link comprising a tubular member having a slot with a projection at one end thereof, a toothed slide having a projection passing through the slot and a scroll wheel engaging the slide, whereby the space between the projections is caused to indicate the extent of the line space.

4. The combination with the platen and spacing mechanism of a writing machine, of an oscillatory collar on the platen, said col-

lar having an enlargement with a socket widest at its upper end, a roller adapted to 50 wedge between the wall of the socket and the platen and a link for oscillating the collar comprising a tubular member, a toothed slide therein and a scroll wheel on the tubular member which engages the slide. 55

5. A line spacing attachment for a writing machine platen comprising an oscillatory collar having an enlargement with a socket widest at its upper end, a roller adapted to wedge between the wall of the socket and 60 the platen, for the purpose set forth, a lug on the collar, a fixed stop adapted to be engaged by the lug and an adjustable link pivoted to the collar for oscillating the same and determining the extent of the spaces between the lines. 65

6. The combination with the platen and line spacing mechanism of a writing machine, of an oscillatory collar on the platen, said collar having an enlargement with a 70 socket widest at its upper end, a roller adapted to wedge between the wall of the socket and the platen, a lever pivoted in the enlargement and adapted to lift the roller out of engagement with the platen and a link 75 pivoted to the collar for oscillating the same.

7. A line spacing attachment for a writing machine platen comprising an oscillatory collar having an enlargement with a socket widest at its upper end, a roller adapted to 80 wedge between the wall of the socket and the platen, cover plates closing the socket, one of said plates having a projection on its inner face and a lever pivoted in the enlargement and adapted to lift the roller out 85 of engagement with the platen, engagement of the lever with the projection acting to lock the lever and ball out of operative position.

In testimony whereof I affix my signature 90 in presence of two witnesses.
